CLAIM

The ornamental design for a display stand, as shown and described.

DESCRIPTION

FIG. 1 is a top front perspective view of a display stand showing the claimed design.

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dashed broken lines in the figures show portions of the display stand or environment that form no part of the claimed design.

The dot-dash broken lines in the figures show boundaries of claimed areas and form no part of the claimed design.

1 Claim, 7 Drawing Sheets

Related U.S. Application Data

29/588,391 is a continuation of application No. 29/564,382, filed on May 12, 2016, now Pat. No. Des. 777,482, which is a continuation of application No. 29/537,088, filed on Aug. 21, 2015, now Pat. No. Des. 756,152, which is a continuation of application No. 29/507,269, filed on Oct. 24, 2014, now Pat. No. Des. 737,081.
